(57) **CLAIM**

The ornamental design for a lid for a beverage container, as shown and described.

DESCRIPTION

FIG. 1 is an elevated perspective view of a beverage container and lid in the open position showing design;

FIG. 2 is a perspective drawing showing the forward side thereof;

FIG. 3 is a perspective view showing the rearward side thereof;

FIG. 4 is a front view thereof;

FIG. 5 is a rear view thereof;

FIG. 6 is side view thereof;

FIG. 7 is another side view thereof;

FIG. 8 is a top view thereof; and,

FIG. 9 is a bottom view thereof.

The broken lines showing the beverage container and portions of the lid are included for the purpose of illustrating environment and form no part of the claimed design.
